METHOD OF AND APPARATUS FOR
FORMING ARTICLESEarl Wensley, Chicago, Ill., assignor to Western
Electric Company, Incorporated, New York,
N. Y., a corporation of New York

Application November 25, 1936, Serial No. 112,668

9 Claims. (Cl. 140—71)

This invention relates to a method of and apparatus for forming articles, and more particularly to a method of and apparatus for forming cables.

In the manufacture of electrical equipment such as, for example, telephone subscribers' sets or radio receiving sets and the like, various pieces of electrical apparatus mounted somewhat closely together must be interconnected in accordance with a predetermined plan to provide the proper circuit connections between the various associated pieces of apparatus. When such articles are made in large quantities, it is frequently desirable to form cables comprised of various wires for interconnecting the pieces of apparatus in a unit, and this cable is usually in the form of a group of insulated strands of wire tied or sewed together and having their ends extending at spaced points from the cable formed by the sewed together group, which ends are connected to the terminals of the pieces of apparatus in the unit after the pieces of apparatus have been assembled. If the cable is made up as a unitary structure, the assembly and interconnection of the various pieces of apparatus is materially expedited.

It is an object of the present invention to provide a simple and expeditious method of and an economically constructed apparatus for forming articles.

In accordance with one embodiment of the invention as applied to the forming of cables for subscribers' telephone sets, a rotatable drum is provided having a plurality of flat surfaces in which pins or nails may be secured in accordance with a predetermined pattern and about which the insulated conductors forming the cable for the subscriber's set may be wound to properly locate the terminal ends of the wire and to group a number of wires which are to be sewn or tied together. In the process of forming the cable, a strand drawn from a suitable source of supply is fixed to one of the pins and then strung around others of the pins on the various surfaces, the drum being rotated to present a new surface to the person winding the cable and the wire being wrapped about the proper pins as the drum is rotated, and until the drum has been rotated through one or more complete revolutions, whereupon the end of the wire is cut off and another wire is then strung about the pins to form a series of strands extending around the drum and about the proper pins on the various faces of the drum. After the desired number of insulated conductors have been so wound, those wires which are to be grouped together in the finished cable may be bound together by wrappings of thread or cord, whereupon the wires may be clipped at predetermined places to thus provide a group of similar or identical local cables.

In the preferred embodiment of the invention, a latching means is provided for holding the drum in any one of its rotated positions, and portions of the drum not being worked upon are enclosed in a resiliently supported cover.

A better understanding of the invention may be had by reference to the following specification when considered in conjunction with the accompanying drawing, wherein

Fig. 1 is an end elevational view of a forming apparatus made in accordance with the invention and adapted to be used in the method constituting the invention; and

Fig. 2 is a plan view of the apparatus shown in Fig. 1.

Referring now to the drawing wherein like reference characters designate the same parts throughout the several views, the numeral 5 indicates generally a cable forming drum having decagonal heads 6 and 7 to which ten cable forming boards 8 are removably secured by means of socket screws 4 positioned in shouldered apertures 3 in the boards 8 and threaded in the heads 6 and 7. Mounted upon the heads 6 and 7 are a pair of trunnions 9 and 10 for rotatably supporting the drum in two bearings 11 and 12 mounted upon a pair of channel shaped standards 13 and 14, respectively.

The standards 13 and 14 carry adjacent their upper ends a pair of angle members 15 and 16 which extend horizontally beyond the outer surfaces of the drum and partially enclose a pair of coil springs 21 and 22. The springs 21 and 22 are not fixed to the angle members 15 and 16 but have their ends secured to a pair of semi-cylindrical cover plates 23 and 24 pivoted on the standards 13 and 14 at 25—25. The cover plates are normally urged by the springs 21 and 22 into engagement with the ends of the angle members 15 and 16 and serve to enclose and shield the lower portions of the drum which are not being worked upon.

Secured to the under surface of the angle member 16 is a bracket 26 carrying a leaf spring 27. The leaf spring 27 has at its upper end (Fig. 1) a stop member 28 which is normally urged into one of the apertures 3 of the boards 8. A rod 29 is fixed to the spring 27 intermediate its ends and interconnects it with a control bar 30 which is slidable in a pair of brackets 31 and 32 mounted upon the angle member 16. The control bar 30 is equipped with a handle 33 at its left end (Fig. 1) and with a push button 34 at its right end (Fig. 1) whereby it may be manipulated from either the right or left side of the drum. Mounted upon the bar 30 is a latch 35 which, upon operation of the bar to move the stop member 28 out of one of the apertures 3, will become effective to hold the stop member in an inoperative position due to the fact that the latch 35 is

pivoted eccentrically on the bar 30 and when the bar 30 is moved to the left (Fig. 1) the latch will drop into the position shown in dotted lines (Fig. 1) to lock the bar 30 in its inoperative position.

5 Each of the boards 8 has a number of pins 40 driven into the outer surface thereof, about which strands of wire may be strung in the process of forming a cable. Due to the fact that the cables are wound around the drum and that 10 there would be a tendency for them to take the shortest distance between two of the pins 40, sleeves 41 have been placed around certain of the pins and the wires may be strung around the pins above the sleeve and thereby held away 15 from the surface of the boards 8 thereby to facilitate the tying of the cables together.

In practicing the method of the present invention, the boards 8 having pins 40 mounted thereon in the desired locations may be positioned upon the heads 6 and 7 and after the 20 drum has thus been prepared, a plurality of similar cables may be formed upon the drum. In forming the cables an operator may withdraw a wire having insulation thereon of a predetermined color from a source of supply (not shown) and after winding it about pins on the board on the drum which is most readily accessible to the operator, the drum having been locked in one of its rotated positions by means of the stop 28, the 25 stop may be momentarily released and the drum rotated in the next position, and after the strand of wire has been wound around the desired pins on the most accessible board 8, the drum may be rotated to another position until the wire has 30 been strung about pins on each of the ten boards 8, or if the wire is to be wound about only a few pins on each board, the latch 35 may be dropped in place so that the drum is freely rotatable in the bearings 11 and 12, and the strand of wire having thus been wound around the pins on each 35 of the boards, it may be severed from the supply thereof and a wiring having insulation of another color may then be wound about certain of the pins on each of the boards. After the required number of strands of wire have been 40 wound about the pins 40, the portions of the wire which in the finished cable are to be sewn together may be sewn or tied in the conventional manner, and after the cables are thus formed they may be cut as required to provide a plurality 45 of separate small cables.

Obviously, if it is desired to make a number of cables of such size that they would not readily fit on one of the boards 8, the pins may be so arranged as to form the desired number of 50 cables.

This and other modifications of the method or apparatus may be made without departing from the scope of the appended claims.

60 What is claimed is:

1. The method of forming cables which comprises stringing a plurality of wires around pins positioned on a cylindrical member, binding together predetermined ones of said wires, cutting 65 the wires at predetermined points, and rotating the cylindrical member to bring selected portions thereof adjacent to the operator.

2. The method of forming cables which comprises placing a plurality of pins in predetermined positions on a cylindrical member, rotating the cylindrical member intermittently to bring selected portions thereof adjacent to the operator, stringing a plurality of wires about the pins in a predetermined manner, binding grouped

wires together at spaced intervals, and cutting the wires at predetermined points.

3. The method of forming cables which comprises placing a plurality of pins in predetermined positions on a cylindrical member, stringing a plurality of insulated wires about said pins, fastening predetermined ones of the wires together, cutting the wires at predetermined points, and rotating the cylindrical member intermittently to bring selected portions thereof adjacent to the operator performing the stringing, fastening and cutting operations.

4. The method of forming cables comprising placing a plurality of pins in predetermined positions on a cylindrical member, fixing a wire to one of said pins, rotating said cylindrical member to a plurality of rotative positions, stringing the wire around predetermined ones of said pins while the cylindrical member is in predetermined ones of its positions, repeating the stringing operation with a plurality of other wires, tying the wires together to form a plurality of connected cables, and cutting the wires at predetermined points to provide a plurality of separate cables.

5. The method of forming cables comprising placing groups of wire supporting elements in predetermined positions upon a cylindrical member, rotating the cylindrical member, stringing wires severally around predetermined supporting elements concurrently with the rotation of the cylindrical member, binding predetermined ones of said wires together at predetermined portions thereof, and cutting the wires intermediate the bound together portions.

6. The method of forming cables comprising placing groups of wire supporting elements in predetermined positions upon a cylindrical member, rotating the cylindrical member, stringing wires severally around predetermined supporting elements during the rotation of the cylindrical member, holding the cylindrical member in predetermined rotative positions, binding predetermined ones of said wires together at predetermined portions thereof while the cylindrical member is held in its rotative positions, and cutting the wires intermediate the bound together portions.

7. A cable forming apparatus comprising a supporting frame, a drum rotatable in said frame, a plurality of wire supporting members positioned upon the surfaces of said drum, and means for locking the drum in a plurality of rotative positions, including a latch rod operable from either side of the drum.

8. A cable forming apparatus comprising a supporting frame, a drum rotatable in said frame, a plurality of wire supporting members positioned upon the surface of said drum, means for locking the drum in a plurality of rotative positions including a latch rod operable from either side of the drum, and a pair of guard members normally urged into proximity with said drum.

9. A cable forming apparatus comprising a supporting frame, a drum rotatable in said frame, a plurality of wire supporting members positioned upon the surface of said drum, means for locking the drum in a plurality of rotative positions including a latch rod operable from either side of the drum, a pair of semi-cylindrical members pivoted to said frame, and resilient means tending to hold said members closely adjacent said drum.
